UNITED STATES PATENT OFFICE

2,241,439

DEVICE FOR PLACING GRAVEL IN HOLES

James D. Ball, Freer, Tex.

Application May 4, 1939, Serial No. 271,669

4 Claims. (Cl. 166—19)

The present invention is directed to a device for placing gravel or similar unconsolidated material in well bottoms. It comprises broadly a slide port and slide valve arrangement to be attached to the bottom of a container which may be lowered into a bore hole. Upon contact with the bottom of the hole the slide valve is caused to slide upwardly and allows material to pass out of the ports of the container.

One object of the present invention is the provision of an apparatus for depositing gravel in an open bore hole, such device to open for release of gravel upon contact with the bottom or with material previously placed into the hole.

Another object of the present invention is the provision of a device having means for diverting the gravel to the sides of the hole.

Another object of the present invention is the provision of a device which remains open after dumping and may be withdrawn from the hole in an open position, thus avoiding a swabbing effect.

A further object of the present invention is the provision of an apparatus for graveling which may be constructed with relatively large ports through which the gravel may be discharged.

It has been customary in completing oil wells to set a tubular strainer or screen in the oil producing formation. It has long been known that, by providing a gravel pack around the strainer, an improved flow of oil from the producing formation may be obtained. According to the present invention, an improved device for depositing gravel in the bottom of an open bore hole is provided which has the advantage that bridging of the gravel within the device during the dumping operation is overcome and which is provided with a trigger so that it remains open after the dumping is completed and may be drawn up to the surface in the open position so that there is no swabbing effect.

Further advantages of the device of the present invention which will hereafter be called a dump bailer bottom will appear from the following description of the accompanying drawing in which—

Fig. 1 is a sectional view of the dump bailer bottom in closed position, and

Fig. 2 is a sectional view of the dump bailer bottom in open position.

Referring to Fig. 1 in detail, numeral 1 designates the lower portion of a bailer or similar container. Attached to bailer 1 by means of screw threads is an inside sleeve 2, the upper portion of which is cylindrical, but the lower portion of

which is cut away to form two ports on opposite sides of the cylinder, the remaining portion of the sleeve being designated by numeral 3. Affixed to the lower end of inside sleeve 2 is a circular piece 4. Covering the ports of inside sleeve 2 is outside sleeve 5 which is of such a size that it may slide along sleeve 2, but which forms a substantially tight closure by contact with sleeve 2 and circular piece 4 when it is in a closed position. The upper portion of outside sleeve 5 is cylindrical, but the lower portion is cut away to form ports corresponding to the ports in outside sleeve 2, the remaining portion of the sleeve being designated by numeral 6.

Attached to outside sleeve 5 and movable therewith are the circular piece 7 and the cylindrical piece 8, the latter being provided with holes 9 and 10 for purposes which will later appear. One end of bolt 11 is passed through an opening in circular piece 4 and is provided with a nut 12, the latter being firmly fastened to piece 4 by welding, as shown in the drawing, or by other suitable means. The other end of bolt 11 is provided with a nut 13, and trigger 14 is attached to the end of the bolt by welding. As shown in Fig. 1, a portion of trigger 14 projects into hole 9 and so holds the valve in a closed position. Bolt 11 has an irregular cross section, and the hole in plate 7 fits snugly around bolt 11 so that outside sleeve 5 is kept from rotating and the ports in sleeves 2 and 5 are maintained in their relative positions.

Plate 4 is provided with a spear head or a wedge-shaped guide surface 15 which causes the bailer to complete the dumping operation and diverts the dumped material to the sides of the hole in a more or less equally distributed manner.

In Fig. 2, the bailer bottom illustrated in Fig. 1 is shown in an open position. It will be observed that outside sleeve 5 has moved upwardly exposing the ports in inside sleeve 2, and that outside sleeve 10 is held fixed in this open position by the projection of the lower end of trigger 14 into hole 10 of tubing 8.

45 The method of using the above described device is as follows:

The bailer bottom is used with a bailer body of any desired length made of tubing, the inside diameter of which is equal to or less than that 50 of the inner sleeve of the bailer bottom. With the bailer bottom set in the closed position, as shown in Fig. 1, the bailer is hung in the hole on a bail line with the top of the bailer hung at a convenient height and is filled from the top. 55 The bailer is then lowered into the hole and upon

reaching the bottom the weight of the bailer body and material being dumped forces the outer sleeve 5 of the bailer bottom up over the inner sleeve 2, opening the port valves and allowing the bailer to start dumping. The port valves are held in the open position by trigger 14 until the bailer bottom is reset, which assures that the bailer will continue to dump as it is picked off the bottom. As the bailer is raised with the valves open, there is no pumping or swabbing effect as would occur if the bailer were raised through a hole containing liquid with the valve in the bottom closed.

From the above description it is obvious that the device of the present invention possesses several advantages. Since the ports are formed in the side of the sleeve, they can be made relatively large. Further, when the valve is open, the outlet is unobstructed by any parts of the valve. This combination of the above mentioned advantages substantially prevents bridging of gravel during the dumping operation. If there should be any tendency for the gravel to bridge during the dumping, the raising of the bailer through the liquid in the hole will wash out through the open valve any gravel remaining in the bailer.

Obviously, many changes may be made in the above described device without departing from the scope of the present invention. For example, an inverted cone may be substituted for the inverted wedge 15 in the bottom of inside sleeve 2, and the size and shape of the valve ports may be altered.

The nature and objects of the present invention having been thus described and illustrated, what is claimed as new and useful and is desired to be secured by Letters Patent is:

1. A device for placing gravel or similar material in the bottom of a bore hole comprising a container adapted to be lowered into a bore hole, side ports in the lower portion of said container, a sleeve valve for said ports arranged outside of said container means attached to said container for locking said slide valve in a closed position 45

and means for raising said valve sleeve upward to expose said parts.

2. An apparatus for dumping gravel into the bottom of a bore hole comprising an inner sleeve 5 provided with a bottom and side ports adjacent said bottom, an outside sleeve fitting slidably around said inside sleeve, said outside sleeve being arranged to cover the ports of the inside sleeve when in its lowermost position, but to uncover them when in its uppermost position, and means connected to said inside sleeve for locking the outside sleeve in its lowermost position.

3. A device for placing gravel in a bore hole comprising a container suitable for holding gravel, said container being provided with side ports adjacent its bottom, a sleeve fitting slidably around the lower portion of said container arranged to close said ports when in its lowermost position and to open said ports when in its uppermost position, a cylindrical member below said sleeve connected thereto with its axis in line with the axis of said sleeve, at least two holes in the wall of said cylindrical member, a pair of arms connected to said container, one of said arms being arranged to cooperate with one of said holes to lock the sleeve in its lowermost position, but to release it when the bottom of the cylindrical member strikes an obstruction with a predetermined amount of force, and the other arm arranged to cooperate with the other hole to lock the sleeve in its uppermost position.

4. A device for placing gravel or similar material on the bottom of a bore hole comprising a container provided with side ports adapted to be lowered into a bore hole, a slide valve attached to said container, said valve being adapted to slide upwardly and open the side ports when it comes in contact with the bottom of a hole, means connected to said container arranged to lock said sleeve valve in its closed position and to be unlocked when the device strikes an obstruction with a prearranged amount of force, and means connected to said container to lock said sleeve in its open position.
